UNITED STATES PATENT OFFICE

138,604

DESIGN FOR A BOTTLE OR SIMILAR ARTICLE

George A. Stevens, Highlands, N. J., assignor to Sperti, Inc., Norwood, Ohio, a corporation of Ohio

Application April 26, 1944, Serial No. 113,376

Term of patent 7 years

(Cl. D58—8)

To all whom it may concern:

Be it known that I, George A. Stevens, a citizen of the United States of America and a resident of Highlands, in the county of Monmouth and the State of New Jersey, have invented a new, original, and ornamental Design for a Bottle or Similar Article, of which the following is a specification, reference being made to the accompanying drawing, forming a part thereof.

The figure is a perspective view of a bottle or similar article, showing my new design.

I claim:

The ornamental design for a bottle or similar article, as shown.

GEO. A. STEVENS.
